(57) **CLAIM**

The ornamental design for a wall light, as shown and described.

DESCRIPTION

FIG. 1 is a perspective view of a light, viewed from the front, left side and bottom, showing my new design;

FIG. 2 is a rear elevation thereof;

FIG. 3 is a top plan view thereof;

FIG. 4 is a front elevation thereof;

FIG. 5 is a bottom plan view thereof; and,

FIG. 6 is a right side elevation thereof, the left side elevation being a mirror image.

1 Claim, 2 Drawing Sheets

Matter enclosed in heavy brackets [ ] appears in the original patent, but forms no part of this reissue; matter printed in italics indicates the additions made by reissue.
